UNITED STATES PATENT OFFICE.

JACOB MARCUS AND JOHN F. BERGEN, OF BROOKLYN, NEW YORK.

TROUSERS-WAISTBAND.

1,321,536.

Specification of Letters Patent. Patented Nov. 11, 1919.

Application filed March 13, 1919. Serial No. 282,333.

To all whom it may concern:

Be it known that we, JACOB MARCUS and JOHN F. BERGEN, both citizens of Poland, both residing at Brooklyn, Kings county, 5 State of New York, have invented certain new and useful Improvements in Trousers-Waistbands, of which the following is a specification.

This invention relates to improvements 10 in trousers-waistbands, pertaining more particularly to the production of a waistband-forming element adapted for production as an article of manufacture of such form as to permit its bodily attachment to 15 the trousers material with a minimum amount of careful attention.

The waistbands of trousers are universally formed of a plurality of plies of material, of which the trousers material forms the 20 outer ply, the remainder of the waistband being generally hidden by being located on the inner side of the garment; as it is desirable that a minimum number of lines of stitching be exposed on the outer surface, 25 this inner formation is generally so arranged as to permit of attachment by blind stitching.

Prior to the present invention, it has been the general practice to produce this inner 30 formation from a multiplicity of elements each formed from a strip of material of the desired length and width, these being generally produced by the tailor and assembled by him when forming the waistband. 35 Various combinations are employed. For instance, a common practice is to provide a stiffener, a binder or binders for the latter, and a lining, these being assembled in such manner that the stiffener is entirely inclosed 40 between the trousers material and the lining, the lining and binder being exposed. As will be understood, the cutting of these elements into strip form necessarily produces a raw edge effect at the opposite edges of 45 the strip, and this forms one reason for the requirement of the binder or binders and the particular folding required to hide these raw edges with their possibilities of fraying.

50 As will be understood, the neat appearance of the garment requires very careful workmanship under these conditions. The stiffener and binder or binders being of different materials and produced separately, 55 the assembling of the stiffener and binder

requires considerable care, since the creasing or fold of the binder must be in a substantially true line—forming an exposed line of the finished waist-band—and the stiffener edge which enters must be approximately straight in order that a good assembly condition may be had—inherently difficult by reason of the character of the stiffener material. After assembly of the 60 binder and stiffener, they must be properly stitched together, and with the lining, stitched to the trousers material to provide the initial assembly of the elements before attempting to complete the band.

The present invention is designed to 70 overcome many of these difficulties by (a) producing a formation in which the raw edge conditions are reduced to a minimum, and (b) providing a composite structure— 75 capable of production as a separate article of manufacture—which provides the complete inner formation of the band when properly attached to the trousers material, the structure being of a type which can be produced in a simple and efficient manner 80 and sold as such for use as desired by the tailor who is not required to provide the careful detail attention to the assembly, the structure itself meeting this particular 85 problem.

To these and other ends, the nature of which will be readily understood, as the invention is hereinafter disclosed, said invention consists in the improved construction and combination of parts, hereinafter 90 fully described, illustrated in the accompanying drawings, and more particularly pointed out in the appended claims.

In the accompanying drawings, in which similar reference characters indicate similar parts in each of the views— 95

Figure 1 is a perspective view of a part of a trousers flap showing the invention applied thereto.

Fig. 2 is a perspective view of a portion 100 of the composite structure forming the article of manufacture, and

Fig. 3 is a detail sectional view showing the structure applied.

The composite structure is shown in Fig. 105 2 and comprises a stiffener element 6 and a liner element 7, these being assembled to produce the structure required for the inner formation of the waistband. As will be seen, the stiffener element is of the usual 110

strip-like formation, but in the present instance, being of any length desired—a number of yards, if the structure is sold by the roll—the strip can be produced by standard methods such as the usual cloth-cutting machines, making it possible to produce a large number of strips—accurate as to width—by a single operation. The liner 7 is also of strip type and can be produced 10 in similar manner, so that the widths of the two elements do not vary throughout their lengths, and such widths can be maintained standard as to size. Obviously, this eliminates the difficulties of cutting the individual strips—with their irregularities—as practised by the tailors.

The stiffener remains unchanged for assembly, but the liner 7 is first manipulated to provide a longitudinal fold 8—which 20 may be considered as a pocket—the opposite walls of which are of substantially equal width, and then providing a return fold—as at 9—upon the inner wall or ply of the initial fold, after which the stiffener is inserted between the walls or plies of the first 25 fold and the four plies thus produced stitched together by a single line of stitches 10, producing the structure of Fig. 2.

Owing to the fact that both folds are in 30 straight lines throughout the length of the liner, these folds can be provided by suitable machines which may also, if desired, be arranged to permit the operator feeding the stiffener strip into position as the folds 35 are made, the embryo assembly then being stitched on the same or a different machine. This is made possible through the fact that the composite structure is not limited as to length, but being of similar cross-sectional 40 configuration throughout, can be cut into desired lengths at will.

Since the liner, when folded, produces the effect of the stiffener, binder and lining elements of the former construction, with one 45 raw edge of the binder and lining omitted by reason of their formation into a single element, it will be understood that the possibilities of fraying at edges are correspondingly reduced. But this provides an additional 50 advantage in that instead of having two raw edges exposed, the exposed structure has the greatly increased strength provided by the fold and the two ply formation of the one piece of material.

55 When the composite structure is to be applied, the free longitudinal edge of the stiffener is placed at the proper point on the inner side of the trousers material 11, as for instance along the upper edge as in 60 Fig. 3, and the structure of Fig. 2 laid on the inner face of the trousers material, the inner ply 8 of the liner being in contact with the material, as shown in Fig. 3. A line of stitches 12 is then run through the 65 five plies preferably between stitches 10 and

the bend of fold 9, after which the free portion of the liner is turned up to the full line position of Fig. 3, and secured in position in any suitable manner, a simple form being to inclose the upper edges of the 70 trousers material, stiffener and liner, by a binder 14.

As will be understood, it becomes a simple matter to run the stitches 12, these being preferably in regular alinement—due solely 75 to the fact that they are exposed, it being seen that this is immaterial on the inner side, since the final bend of the liner is not made on the basis of the line of stitches 12 but the stitches 10 which were originally 80 provided in the composite structure and therefore having a greater likelihood of extending in a regular alinement. Not only is this advantage present in the final folding of the liner, but the additional advantage is 85 present that any strains which might be placed on the liner are not made effective on the stitches 12 but on stitches 10, so that such strains do not affect the appearance of the exposed stitches on the front of the 90 trousers.

While the location of stitches 12 is such as to bring them close to the upper edge produced by fold 9—substantially impracticable where the two raw edge structure 95 is present at this point by reason of liability of being torn loose—the integral formation at this point and the double thickness of the material acts to increase the security of position of the stitches for obvious reasons. 100

While we have herein disclosed a preferred embodiment of our invention, and disclosed a way in which it may be employed, it will be readily understood that changes and modifications therein may be 105 found desirable or necessary in meeting the various exigencies of use, and we desire to be understood as reserving the right to make any and all such changes or modifications therein as may be found necessary or essential in so far as the same may fall within the spirit and scope of the invention as expressed in the accompanying claims when broadly construed. 110

Having thus described our invention, 115 what we claim as new is:

1. As a new article of manufacture, a composite structure for application to the trousers material as a unit to produce the inner formation of the trousers waistband, 120 said structure comprising a stiffener element, and a liner element, said elements being stitched together to form a four-ply assembly on the stitching line, three of the plies being formed from the liner element. 125

2. A trousers waistband comprising a stiffener and lining elements assembled with a stiffener edge seated within a pocket one wall of which is in integral double-ply formation and with the elements assembled 130

by stitching through the pocket and its walls, said assembly being secured to the trousers material by stitching through the pocket intermediate the outer end of the 5 pocket and the first-mentioned stitching, said lining element being folded to overlie both stitchings, whereby the first-mentioned

stitchings will be rendered blind and serve to sustain the strains of the fold.

In testimony whereof we have signed our 10 names to this specification this eleventh day of March, 1919.

JACOB MARCUS.
JOHN F. BERGEN.
